CLAIM

The ornamental design for shoe upper, as shown and described.

DESCRIPTION

FIG. 1 is a perspective view of the shoe upper embodying the new design;

FIG. 2 is a front elevational view thereof;

FIG. 3 is a rear elevational view thereof;

FIG. 4 is a top plan view thereof;

FIG. 5 is a right side elevational view thereof; and,

FIG. 6 is a left side elevational view thereof.

FIGS. 1-6 show an outsole in broken lines. The outsole is shown for environmental purposes and does not form any part of the claimed design.

The broken lines which form the bounds of the claimed design form no part thereof.
